UNITED STATES PATENT OFFICE.

GEORGE A. AMSDEN, OF LITTLETON, MASSACHUSETTS, ASSIGNOR TO THE LAMSON COMPANY, OF BOSTON, MASSACHUSETTS, A CORPORATION OF NEW JERSEY.

CABLE-CARRIER APPARATUS.

1,226,740.

Specification of Letters Patent. Patented May 22, 1917.

Application filed December 26, 1913. Serial No. 808,718.

To all whom it may concern:

Be it known that I, GEORGE A. AMSDEN, a citizen of the United States, residing at Littleton, in the county of Middlesex and State of Massachusetts, have invented certain new and useful Improvements in Cable-Carrier Apparatus, of which the following is a specification.

This invention relates to cable carrier systems in general; the preferred construction hereinafter described exemplifying the invention as applied to a drop-station in what is known in the art as a high line cable carrier system; the term drop station being used in this particular connection in the same sense in which this term is used in the joint application of George A. Amsden and Rothesay P. Kidder, entitled Drop-station for cable carrier apparatus and the like, Serial Number 792,888, filed August 1, 1913.

In certain of its aspects the present invention may be regarded as an improvement upon the construction disclosed in the said joint application.

One of the objects of the present invention is to permit of the insertion of the carrier, to be despatched, upon an outer side of the station rather than from a point between the ascending and descending limbs of the cable.

I have further aimed to render the station more compact and sightly, and, further, an important object of the present invention is to reduce the span across which a carrier must travel by momentum or gravity, unaided by the cable, when passing by a station of the character to which the present construction more particularly relates.

I further aim to avoid unnecessary reverse bending of the cable; or in other words, when the strands of the cable have been bent by passing over a pulley, one side of the cable at such point is subjected, in effect, to compression, or at any rate to reduced tension, while the other side is subjected to a relatively greater tensile effort; and thereafter, while the cable obviously straightens out, as it leaves a pulley and the stresses upon opposite sides of such portion thereof are then equalized, such portion will, as far as practicable, be forced to bend around each succeeding pulley in such fashion that the side thereof which was subject to said greater tensile effort will again be the more remote from the axis of rotation of the pulley upon

which it then rides, and will, hence, again be subject to the greater stress.

On the other hand, in systems now in use, the cable passing down or sidewise through a drop or other way station is forced to bend first to one side thereof as it passes one pulley and then, after being straightened out, toward the opposite side thereof, which action, although a cable may be quite flexible, tends to ultimately cause appreciable wear of the strands therein.

I have further sought to accomplish the above objects while maintaining the number of pulleys at a station at a minimum, to wit, three.

This and other objects of my invention will be hereinafter referred to and the novel elements and combination of elements whereby said objects may be attained will be more particularly set forth in the claims appended hereto.

In the accompanying drawings which form a part hereof and in which like reference characters designate like parts there has been exemplified a cable system drop-station in which are embodied preferred forms of the essential, together with certain relatively non-essential but useful features of the invention; but I am aware of various changes and modifications which may be made herein and of various other applications and embodiments of the invention in carrier systems and hence do not desire to be limited in any way other than by the scope of said claims.

Referring to the drawings:

Figure 1 is a front elevation of the preferred drop-station above referred to.

Fig. 2 is a side elevation of the same viewed from the left.

Fig. 3 is a similar elevation viewed from the right.

Fig. 4 is a top or plan view of the improved cross-over drop station.

Fig. 5 is a partial rear elevation.

Fig. 6 is a detail section taken on line VI—VI of Fig. 5.

Fig. 7 is a detail section taken on line VII—VII of Fig. 6.

Referring first to Fig. 1, the main tracks, it will be observed, are both preferably so disposed as to convey the carrier with its grip pointing down, and the outgoing track from the cashier station, not shown, has been designated 1, and of course constitutes

the delivery track to the way stations; while the incoming track 2 to said cashier station constitutes the receiving track for said way stations.

In the preferred form of the invention but a single endless cable 3 is provided, which constitutes the means for elevating carriers from the way station or stations to the main receiving track as well as for propelling them along both of the main tracks; this cable being looped down through the station in a manner distinctively new to the art. I do not desire, however, to be limited in any way to the single endless cable except where in certain of the claims such construction is specifically referred to, since it is obvious that other means may be employed for elevating or otherwise moving the carrier from the clerk's station to the main track. It is regarded as preferable, however, to employ but a single endless looped cable, owing to the simplicity of construction which is rendered possible by the use of this propelling device.

The cable 3 propels the carriers along the main tracks in the direction of the arrows indicated adjacent thereto, and the cable of the receiving track passes downwardly around the idler or pulley 4 to the pulley 5, at the station proper, and thence up around the pulley 6 and on to the next way station or to the cashier's station, as the case may be.

The idlers or pulleys 4 and 6 are preferably mounted upon the same spindle 7; being provided with loops 7' adapted to space them apart and to center them properly within the supporting bracket 8. The pulley 5 is mounted in a casing 9 which preferably substantially completely incloses the same and thereby avoids possible injury to the person or garments of the operative.

As shown in Fig. 1, this casing is rigidly mounted upon an upright 10 and has extending rearwardly therefrom a bracket 11 which supports the looped portion 12 of an independent track which delivers carriers to the station from a switch 14; the latter being adapted in a known manner to selectively remove carriers from the track 1 which are destined for a given or predetermined station.

The construction of the switch 14 is well known in the art and hence need not be herein described. Carriers which descend the independent track are received in the said looped portion thereof and may be removed from between the flared extremities 15 of the track rails.

The descending limb of the loop in the cable passes through a suitable opening 16 in the casing 9 and after passing around the pulley 5 emerges from said casing at a corresponding opening 17. It may be here noted that the sides 18 of this casing are

preferably separable from the body thereof so that access may readily be had to the pulley 5.

The delivery track or guide 19 extends up from the left hand side of the casing 9, as viewed in Fig. 1, substantially to the receiving track 2; a gap in the latter, normally closed by a bridge or bridge elements 20, shown in detail in Figs. 6 and 7, serving to permit of the passage of a carrier from the delivery track to said receiving track.

The bridge preferably consists of two oppositely movable elements 20, which are respectively hinged at 21; each element 20 being of sheet metal, the longitudinal curled edges of which are curled and cut away as indicated in Figs. 4, 5, 6 and 7.

The curled outer edge of each bridge element is centrally recessed as at 22 for the reception of the coil spring 23, one end of which is in engagement with a suitable fixed point, as for example, a portion of the auxiliary bracket 8' which is carried by the bracket 8, as shown in Fig. 6, and the other end 24 of which bears against the corresponding element 20 so that each of the elements normally tend to move toward the position in which they are shown in full in Figs. 1, 4, 5 and 6.

The ascending carrier swings upwardly and apart the bridge elements; outward movement of the latter being limited by suitable stops 25 which extend upwardly from the respective brackets 8'; the bases of these stops together with lugs 26, also upon said brackets 8', constituting the bearings of the hinge pins 21. The tips 25' of the stops may, if desired, be made of soft rubber to reduce noise. The inner edges of the plate like elements 20 are curled into conformity with the diameter of the preferably round rods which constitute the track, and the ends of these curled edges or corners of the plates are cut away below to provide for proper engagement of the upper sides 110 thereof with the reduced ends 27 and 27' of the track members or track rods 2 (see Fig. 7), the end 27' also being sloped upwardly to facilitate the emplacement of the carrier on the receiving track. Sufficient 115 clearance 28 is provided between the outer ends of the track members 19 and the reduced ends 27' of the track 2 to permit of the free passage therebetween of the retaining lugs 29' or like parts common to the 120 carriers 29 adapted for use in systems of this character. The construction of these carriers need not be herein particularly referred to, since they are in very common use in the art and have been fully described 125 in my Patent #960,617.

Obviously when the bridge is in its closed or normal position a through carrier *en route* along track 2 past the station shown will traverse the gap in engagement with 130

the inner curled edges of the elements 20; while a carrier being delivered from the station to said track will lift the bridge and jump the clearance spaces 28.

5 Track 19 is bent outwardly somewhat, as at 31, to facilitate the emplacement thereon of the carriers being despatched; the track members being spread to provide the usual carrier lug receiving apertures 32, or as we 10 may term it in conformity with the usage in the art, aperture 32. Above the latter is a bracket 33 which carries a carrier grip opening cam 34 and a grip closing cam 35.

15 The functions of these cams have been set forth in the joint application above referred to and they will hence be hereafter but briefly referred to.

Above the bracket 33 is a second bracket 36 which carries a cam 37; the purpose 20 of which will also be hereinafter referred to; while a determined distance above cam 37 is a movable grip opening cam 38, mounted on a rock shaft 38', and movable into and out of its operative position by means 25 of the following mechanism: To the left of Fig. 1 and right of Fig. 5 is a rod or strip 39, which together with its spanning arms 40, constitutes an actuating frame or member for said cam 38. The arms 40 are fixedly mounted on a rock shaft 41, journaled in suitable brackets, which carries a crank arm 42, which, when rotated counter-clockwise, as viewed in Fig. 3, raises and thereby lifts a bent link 43, which in turn elevates 35 a crank arm 44 on shaft 38' and swings the toe of such cam into its dotted line position shown in Figs. 2 and 3.

40 When so disposed cam 38 is adapted to push open the pivoted grip element of the carrier ascending from the station which frees the carrier from the cable with which it had been in engagement and permits it to drop back by gravity until said grip element encounters the downwardly sloping 45 upper or operative surface of the cam 37; whereupon the carrier grip reengages the cable and the carrier again travels upwardly toward the receiving track 2. As soon as cam 38 moves out of the path of 50 the carrier the latter is then free to pass upwardly on to track 2 and pursue its journey. Cam 34 opens the grip of the carrier if it be not already open, when the carrier is inserted at 32, and the cam 35 55 closes the grip on the ascending limb of the cable, in a known manner, as the carrier is lifted by the hand of the operator.

60 The frame which actuates cam 38 is controlled by the carriers traversing the main track 2 past the station; bar 39 being normally held in the path of these carriers, both by gravity and by means of a helical spring 45 suitably connected at one end to a bracket 46 and at the other to a collar 47 65 upon the rock shaft. The left hand ex-

tremity of the rod 39, as viewed in Fig. 1, is outwardly curved, as shown in Fig. 4, so that an approaching carrier may wipe this rod aside and thereby swing cam 38 into its operative position, and as long as said 70 carrier is in contact with said rod, cam 38 will prevent the delivery of any carrier being despatched from the way station to the main track; thus preventing collision. Excessive movement of the cam 38 75 and its actuating frame is prevented by stops 48 and 49 upon the hub of the cam 38; said stops being respectively adapted to engage the opposite sides of the bearing bracket 50, as indicated in Figs. 2 and 5. 80

A grip opening cam 51 frees a carrier approaching the gap which is bridged by elements 20, immediately before it passes on to said elements; this cam operating in a known fashion; and the momentum of the carrier then carries it over the bridge and on to the section of track 2 therebeyond. 85

As shown in Figs. 1 and 5, a slight depression or dip 52 is provided in this section immediately beyond the extremity 27' 90 thereof (Fig. 7), the purpose of which is to lower the carrier momentarily toward the cable until the open jaws of the grip straddle the latter. At substantially the lowermost point of this slight drop is a grip closing cam 53, which, as the pivoted jaw of the grip rides therealong, closes the latter in a known manner; so that the carrier is thence propelled along the main track 2 by the cable. Cam 51 of course only unlocks the 95 grips of through carriers; the carriers ascending from the station, after they have once succeeded in passing the cam 38, being thereafter not subject to the action of a grip opening cam until they encounter the cam 100 51 of the next station beyond, or a corresponding cam at the central station. 105

In this construction as in that disclosed in the joint application above referred to, it will be noted that the through tracks 1 and 110 2 have the rails thereof so disposed as to convey carriers with their covers up or in other words, with the carriers disposed flatwise.

A carrier selected for delivery at the station is propelled up the switch rails by the cable and is then disengaged from the latter by the grip opening cam 55, which pushes or wipes open the pivoted grip jaw and frees the cable; a cord or releasing bracket 56 supported from the rails 19, aiding in freeing the cable from its engagement with the grip in a known manner. 115

The mode of operation of the apparatus given by way of exemplification is briefly 120 125 as follows:

Assuming first that a carrier is *en route* past the station shown; its grip being in engagement with the cable 3. Upon encountering cam 51, the grip is opened and the 130

cable drops down; the portion thereof until then engaged by said grip passing down through the loop and the carrier proceeding along track 2 and over the closed bridge by 5 momentum.

It then passes on along the further section of track and dips down until its grip can be reengaged by cam 53 with the cable, after which it is propelled on to the next 10 way station where the successive disengagement and reengagement of the cable is again effected, and so on until it is delivered, let us say, to the cashier. As each way station is passed the through carrier swings aside 15 the movable cam actuating-frame thereof, which promptly resumes its position in the path of succeeding carriers as soon as the passing carrier permits it to.

If now a carrier be despatched from the 20 way station shown, while cam 38 is held in its operative position by a passing carrier, so that the grip of the carrier being despatched encounters cam 38 before the latter moves away from the cable, the said despatched carrier will be freed from the cable 25 and will fall by gravity until its grip is reclosed by cam 37. The cable then re-lifts this carrier and unless a through carrier should chance to be immediately behind the 30 first the despatched carrier will have an opportunity, after this one reciprocation thereof, to emerge on to the main track through or past the bridge; said carrier swinging apart the elements 20 in so doing. 35 The latter immediately thereafter move back to their closed or normal positions.

A carrier *en route* along track 1 and intended for the station shown, will be selectively removed from said track by the 40 switch; its grip will be opened by cam 55 and the cable will be removed therefrom by gravity and by the action of bracket 56; the carrier then descending track 19 and coming to rest in the loop 12 of the latter, 45 from whence it may be removed at 15.

Particular attention is directed to the fact that by reason of the provision of the novel loop in the cable of the carrier system in question, but a very short gap need be provided in the main track 2 across which a carrier *en route* over said track past the way station need travel unattached to the cable. The station is furthermore very compact and its mechanism is therefore less in evidence than where the upper pulleys 4 and 6 are placed apart in substantially the same plane.

I particularly desire to call attention to the ease with which a carrier may be inserted at 32, by reason of the fact that the track, upon which said carrier travels up from the station, may be directly faced by the operative with no intervening track or cable such as is present in the construction

set forth in the joint application above referred to. 65

An arrangement of the pulleys such as has been herein described, when viewed in side elevation, causes the cable passing through the station to assume substantially the form 70 of a flattened letter O instead of an elongated U, as in said joint application, and in large measure insures that the cable will be repeatedly bent toward a determined side thereof as it passes around the successive 75 pulleys; instead of being reversely or oppositely bent after it has been straightened out upon its emergence from a pulley groove.

This substantial elimination of such reverse bending of the cable at the way stations, I consider, tends to prolong the life 80 of the cable by reducing the extent of play of the fibers or strands thereof with respect to each other.

In conclusion I may call attention to the 85 advantages which flow from the provision of the bridge adjacent the ascending limb of the cable running through the station, outside of the space inclosed by said cable, since this arrangement, as previously intimated, permits the carrier to be freely inserted upon a side of the station which faces outwardly and, further, places the bridge upon the same side of both of the revolute elements or pulleys the tops of which are 90 substantially at the level of the main or through track. 95

It also permits the axes of rotation of all of the pulleys at, or substantially at, the 100 station being disposed in a common vertical plane.

I do not desire to be limited to any particular disposition of the outwardly facing side of the station at which the carriers may be inserted, since while in the exemplified 105 construction the said side faces at an angle of 180° to the line of travel taken by the carriers immediately after being despatched from said station, or when passing the same over the bridge, the said side may obviously be made to face at any angle to said line by bending the vertical or auxiliary tracks in a known manner. When, however, the said side is faced as shown it permits of the carriers being despatched from the station so 110 that they enter the through track flatwise (without additional bending of the auxiliary track), in contradistinction to edge-wise, so that a really considerable number of desirable results are attained with an exceedingly simple construction. 115

Having thus described my invention what I claim is:

1. Cable carrier apparatus comprising, a 125 main track, and a drop-station having a pulley adjacent said main track and an auxiliary track leading around said pulley to said main track, said auxiliary track having

the rails thereof bent to substantially the same radius, around said pulley and thereby adapted to support carriers flatwise thereupon when said carriers are passing around said pulley, and means for propelling carriers along said main and auxiliary tracks, said auxiliary track having means to permit of the emplacement of a carrier thereupon from an outer side of said drop station.

2. Cable carrier apparatus comprising a way, a carrier to travel along said way and separable therefrom, said way having means for receiving parts of said carrier to permit of the emplacement of said carrier upon and its removal from said way, a station along said way, pulleys at said station, and an endless cable for propelling carriers from said station at least to said way, said cable at said station being guided by said pulleys, said pulleys being mounted upon but two axes of rotation and each portion of said cable successively passing over each of said pulleys.

25 3. Cable carrier apparatus comprising a way, a station along said way, three pulleys at said station, and a cable for propelling carriers from the station proper at least to said way, said cable at said station being guided by said pulleys, two of said three pulleys being mounted upon a common axis of rotation disposed adjacent said way.

4. Cable carrier apparatus comprising a way, a station along said way, three pulleys at said station, and a cable for propelling carriers from a despatching part of said station at least to said way, said cable at said station being guided by said pulleys, two of said three pulleys being mounted upon a common axis of rotation disposed adjacent said way and substantially directly above the axis of the third pulley.

5. Cable carrier apparatus comprising a way, a station along said way, pulleys at said station, and a cable for propelling carriers from a despatching part of said station at least to said way, said cable extending down from the way, around one of said pulleys and back to the way in substantially the form of a flattened O.

6. Cable carrier apparatus comprising a way, an endless carrier-propelling cable, a station having pulleys to guide said cable, the axes of rotation of all of said pulleys being in a substantially common vertical plane.

7. Cable carrier apparatus comprising a way, a station, flexible means to propel carriers from said station to said way and to propel carriers along said way, a portion of said flexible means running through said station, means to disengage a carrier approaching said station along said way, from the part of said flexible means with which

it is in engagement, said moving carrier 65 passing said station in part at least by its momentum, means for reengaging said carrier with a part of said flexible means, and a plurality of co-acting elements to guide the portion of said flexible means which runs 70 through said station, said co-acting elements being in different planes and being one behind the other, as viewed from the outer side of one of said elements, to permit of the span between said disengaging and reengaging means being reduced substantially to a minimum.

8. Cable carrier apparatus comprising a way, a station, flexible means to propel carriers from said station to said way and to 80 propel carriers along said way, a portion of said flexible means running through said station, means to disengage a carrier approaching said station along said way, from the part of said flexible means with which it is in engagement, said moving carrier 85 passing said station in part at least by its momentum, means for reengaging said carrier with a part of said flexible means, and two pulleys adjacent said way and a lower 90 pulley relatively remote therefrom, to guide the portion of said flexible means which runs through said station, the overall distance, measured in the plane of one of said two pulleys, from the point in the periphery of 95 said last mentioned pulley which is most remote from the point of tangency of the depending limb of the cable which is in contact therewith, across to the projection on said plane of the corresponding point of the 100 other of said two pulleys, which corresponding point is most remote from the point of tangency of the other depending limb of said cable, being less than the sum of the diameters of said three pulleys.

9. Cable carrier apparatus comprising a way, a station along said way, an endless cable for propelling carriers from said station to said way, and revoluble elements over which said cable passes, each disposed to substantially avoid reverse bending of said cable as its portions successively contact with said elements, said cable being looped around said elements and having the points of tangency of each limb of the loop with the elements at the respective ends of said limb, both upon the same side of the respective axes of said last mentioned elements.

10. Cable carrier apparatus comprising a way, a station along said way, an endless cable for propelling carriers from said station to said way, and elements substantially at said station over which said cable passes, each disposed to substantially avoid reverse bending of said cable as its portions successively contact with said elements, said cable being looped around said elements and having the points of tangency of each limb of

the loop with the elements at the respective ends of said limb, both upon the same side of the respective axes of said last mentioned elements.

5 11. Cable carrier apparatus comprising a main track, a drop-station along said main track, flexible means for propelling carriers from a point in said drop-station to said main track and thereafter along said track
10 from said station, said drop-station having revolute elements over which said flexible means pass, each of said elements being disposed with respect to the others to substantially avoid reverse bending of the portions
15 of said flexible means which successively encounter said elements, said cable being looped around said elements and having the points of tangency of each limb of the loop with the elements at the respective ends of
20 said limb, both upon the same side of the respective axes of said last mentioned elements.

12. Cable carrier apparatus comprising a main track, a drop-station along said main track, flexible means for elevating carriers to said track and for propelling carriers along said track, said drop-station having revolute elements in contact with portions of said flexible means and driven thereby, said elements being disposed with respect to each other to substantially avoid reverse bending of said portions as they successively encounter said elements, said cable being looped around said elements and having the points of tangency of each limb of the loop with the elements at the respective ends of said limb, both upon the same side of the respective axes of said last mentioned elements.

40 13. Cable carrier apparatus comprising a main track, a drop-station along said main track, flexible means for propelling carriers along said track, said drop-station having revolute elements in contact with portions of said flexible means and driven thereby, each of said elements being disposed with respect to each other to substantially avoid reverse bending of said portions as they successively encounter said elements, said cable being looped around said elements and having the points of tangency of each limb of the loop with the elements at the respective ends of said limb, both upon the same side of the respective axes of said last mentioned elements.

45 14. Cable carrier apparatus comprising a way, a drop-station along said way, a cable running through said station to elevate carriers to said way, said cable being looped, and a bridge in said way to one side of the loop in the cable, said bridge being outside of said loop and adjacent the ascending limb thereof.

55 15. Cable carrier apparatus comprising a

way, a drop-station along said way, a cable 65 running through said station to elevate carriers to said way, said station having two pulleys adjacent said way, said cable passing around said pulleys and being looped, and a bridge in said way to the same side 70 of both of said pulleys, said bridge being adjacent the ascending limb of the loop, in said cable.

16. Cable carrier apparatus comprising a way, a drop-station along said way, a cable 75 running through said station to elevate carriers to said way, said cable being looped and the ascending limb of the loop being upon the side of the station which faces in a direction opposite to that in which carriers travel from said station when despatched therefrom, a movable grip opening cam for releasing the grip of carriers being despatched from said station, and means, controlled by carriers *en route* along said 85 way past said station, for actuating said cam.

17. Cable carrier apparatus comprising a way, an endless carrier-propelling cable, a station having pulleys to guide said cable, 90 the axes of rotation of all of said pulleys at said station being in a substantially vertical common plane.

18. Cable carrier apparatus comprising a way, a carrier, a drop-station along said way, said way having a vertically opening gap therein at said station, an endless cable running through said station to elevate said carrier to said way, said carrier adapted to grip said cable to be elevated thereby and a 100 bridge for said gap over which carriers *en route* past said station may travel, said bridge adapted to be opened to permit of the emplacement on said way of carriers despatched from said drop-station, and being disposed adjacent the ascending limb of said cable, said limb being to that side of the station which faces in a direction opposite to that in which carriers travel along said way after being despatched from said 110 station.

19. Cable carrier apparatus comprising a way, a drop-station having a pulley adjacent said way, a cable running up over said pulley to elevate carriers from the station 115 proper, means to guide said carriers flatwise around said pulley onto said way, said means being upon the side of said station which faces in a direction opposite to that in which carriers travel when moving along said way after being despatched from said station.

20. Cable carrier apparatus comprising a way, a drop-station having a pulley adjacent said way, an endless cable running up 125 over said pulley to elevate carriers from the station proper, means to guide said carriers flatwise around said pulley onto said

way, said means being adjacent the ascending limb of said cable, and said limb being to an outer side of the station, which side faces in a direction at an angle to that in which carriers travel along said way after being despatched from said station.

In testimony whereof I have affixed my signature, in the presence of two witnesses.

GEORGE A. AMSDEN.
